SAND CATCHER

Otis H. Crabtree, Long Beach, Calif.

Application April 20, 1945, Serial No. 589,294

12 Claims. (Cl. 103—179)

1

This invention relates to well pumps and relates more particularly to means for trapping sand and foreign material borne in the fluid pumped from a well to prevent seizure or freezing of the pump within the well tubing which supports and houses it so that removal of the pump from the well tubing may be easily accomplished when such removal is desired.

Certain wells require pumping operations for extracting the fluid from the earth formations into which said wells are drilled. For this purpose, a string of tubing is extended into the well and a reciprocating pump is mounted within said tube, usually in its lower end portion, for the purpose of pumping out the fluid entering the well from the earth formations. In many oil wells the fluid carries a high proportion of sand and other foreign materials. For the most part, these sands and foreign materials are pumped out with the fluid but much of them settle back around and within the pump to clog the pump and interfere with its normal operation. When an unduly large amount of sand has accumulated in and around the pump, it becomes desirable to withdraw the pump from the well for cleaning and, if necessary, to replace worn parts. Frequently, however, it is found that the pump has become frozen within the tubing. This freezing or seizure may be caused by sand accumulations packing around the parts of the pump and the tube by means of which the pump and the tube are separably connected. In bottom lock pumps, the hold-down shoe on the tube and the hold-down mandrel on the pump frequently clog up with sand to such a degree as to prevent desired separation of these parts when withdrawal of the pump is desired. In top lock pumps, the lock sleeve on the top lock mandrel becomes clogged by said accumulations to such a degree as to prevent its being dislodged from holding engagement with the top lock assembly of the casing tube.

This invention has for a primary object the provision of means in a well pump for keeping sand and other foreign material from clogging the pump structure to such a degree as to make difficult or impossible the removal of said pump structure from the well.

Another object of the invention is to provide a well pump incorporating means for catching or trapping sand which may be in the fluid being pumped and in which said sand catching or trapping means is of such capacity as to permit operation of the pump over a long period of time before the need arises for withdrawing the pump from the well for cleaning or repair.

2

Another object of the invention is to provide a well pump incorporating elongated sand trapping means wherein a large quantity of sand may be accumulated and thereby kept from clogging the operating and connection portions of the pump mechanism for a long operating period.

Another object of the invention is to provide a well pump of novel structure and arrangement incorporating means for trapping a relatively large quantity of sand and foreign material borne in the fluid pumped by said pump whereby fouling of separable anchor means of the pump is delayed for a long period of time.

Another object of the invention is to provide a well pump structure incorporating sand catching and trapping means of simple, efficient and durable design and arrangement whereby the efficient life of the pump is extended.

The various objects and features of my invention will be fully understood from the following detailed description of typical preferred forms and applications of the invention, throughout which description reference is made to the accompanying drawings, in which:

Fig. 1 is a semi-diagrammatic longitudinal view of a well pump according to the invention as incorporated in a traveling barrel type pump showing the manner in which the pump mounts in a well tubing.

Fig. 2 is an enlarged broken longitudinal sectional view more clearly illustrating the upper portion of the pump shown in Fig. 1.

Fig. 3 is a view similar to Fig. 2 showing the lower portion of the pump.

Fig. 4 is a semi-diagrammatic longitudinal view of a traveling plunger type of pump embodying the invention showing the manner in which the pump mounts in a well tubing.

Figs. 5, 6 and 7 are each enlarged longitudinal sectional views of the respective upper, intermediate and lower portions of the pump shown in Fig. 4.

The invention may be embodied in various types and forms of well pumps. The following specification will describe two preferred forms of sand catching or trapping means as applied to typical pump structures. It should be understood, however, that other like pump structures may embody the invention to achieve the objects and purposes of the invention.

Figs. 1, 2 and 3 illustrate an insert traveling barrel type of pump with a bottom lock and incorporating a preferred form and sand catching means. The pump may generally comprise a traveling barrel 10, a stationary plunger 11, means such as a string of sucker rods 12 for reciprocat-

ing the barrel from the surface of the well, a housing or tubing 13 for the pump, anchor means 14 for separably connecting the pump and tubing, and means 15 for collecting, trapping, catching or otherwise accumulating sand and foreign material in the fluid passing through the pump, said latter means hereinafter being termed a sand catcher.

The barrel 10 may be of typical construction involving a top cage 16 in which is arranged a ball 17 and a seat 18 to permit passage of fluid through the cage only upon downward movement of the barrel 10. Said cage may be connected to a string of sucker rods 12, for instance to the lowermost sucker rod 20 of said string, by means of its neck 19. The top cage 16 may be connected to an upper barrel bushing 21 which carries an upper length of tubing 22 of the barrel. The barrel part 22 may be connected by means of an adapter 23 with a lower length of tubing 24 which may carry a lower tube bushing 25 which forms the lower end of the barrel. A plurality of liners 26 may be disposed within the lower tubing 24 and between the adapter 23 and the lower tube bushing 25.

The above-described barrel structure is arranged for reciprocatory movement from the surface of the well by means connected with the string of sucker rods 12 and is arranged to telescope over the pump plunger 11 which, in this instance, is fixed. Said plunger may include a standing cage 27 in which is arranged a ball 28 and a seat 29 which cooperate to permit passage of fluid through the cage only upon upward movement of the barrel 10. Said cage 27 may be connected, as by means of a top plunger bushing 30, to a plunger 31 which carries a plunger adapter 32 at its bottom end.

The barrel 10 and the plunger 11 are so arranged and constructed as to provide an elongated chamber 33 within the upper tubing 22 and between the upper barrel bushing 21 and the adapter 23. The reciprocatory movement of the barrel 10 is, therefore, limited by the length of the tubing 22, since the cage 27 is disposed in said chamber.

The above-described pump has fluid passages which comprise the opening or passage 35 in the tube 31, an axial bore 36 in the bushing 30, ports 37 in the standing cage 27, the chamber 33, an axial bore 38 in the barrel bushing 21, and the ports 39 in the top cage 16. It is evident that an up stroke of the barrel 10 will cause fluid to be drawn into the chamber 33 by unseating the ball 28 to allow the fluid to enter said chamber through passage 35, bore 36 and ports 37. A subsequent down stroke of the barrel will cause displacement of the fluid in the chamber 33 through bore 38 and through the ports 39 by unseating the ball 17.

The pump is disposed in the casing or tubing 13 which may comprise the lowermost section 40 of a number of such sections which are coupled together in a manner common in well construction. Said lowermost tubing section 40 carries the pump or, at least, the stationary portions thereof which, in this case, is the plunger 11.

The means 14 are provided so that removal of the pump from the casing 13 may be effected. Said means may comprise a lock hold-down shoe 45, a lock hold-down mandrel 46 disposed within the shoe, a lock hold-down sleeve 47, and a nut 48 engaged with the mandrel.

The shoe 45 may comprise a substantially cylindrical member having external threads for

connection at 49 with the lower end of the tubing section 40. The shoe is provided with an axial chamber 50 and is also provided with an inreaching annular cam bead 51 near the lower end of said chamber. The upper end of the shoe is provided with a conical seat 52 to receive the coned end 53 of the sleeve 47.

The mandrel 46 is formed as a cylindrical element and has a through passage 54. The upper end of the mandrel is reduced in diameter and the sleeve 47 and nut 48 are fitted on said reduced part, the nut being threaded on as at 55. A lock hold-down adapter 44 is used for connecting the mandrel assembly and the pump plunger assembly 11, said adapter having threaded connection at 56 with an extension of the reduced portion of the mandrel 46 and with the plunger adapter 32. The lock hold-down adapter 44 has a passage bore 43.

The portion of the mandrel 46 disposed within the shoe 45 is longitudinally slotted at 57 to provide resilient fingers 58 which, at their lower ends, are provided with cam portions 59 normally positioned below the cam head 51 of the shoe. The portions 59 comprise a conical enlargement of the fingers 58 having a nominal diameter greater than that of the internal diameter of the cam head 51.

From the foregoing it may be seen that when the pump is being assembled into the tubing 13 and, as the lower ends of the mandrel fingers 58 approach the shoe, the conical portions of the cams 59 will engage first, the conical seat 52 and then the cam head 51. This causes inward springing or flexing of the fingers upon each such engagement, until the mandrel resides in the chamber 50 with the sleeve 47 engaged with the seat 52 and the finger cams 59 below the cam head 51. During a normal operation of the pump, the separable anchor for the pump, thus provided, will maintain the plunger in the desired fixed position. However, an increased pull upon the pump for the purpose of dislodging and removing it will cause the fingers 58 to flex inwardly past the cam head 51 and the walls of the seat 52. Such a pull may become effective when the pump barrel is raised to cause the adapter 23 to abut against the bushing 30. It is further evident that the aforementioned removal of the pump can be accomplished only if the fingers 58 are free to flex inwardly. Should sand accumulations clog the chamber 50 to such a degree as to fill up the slots 57 of the mandrel, said fingers will be unable to flex and the pump cannot be removed. In practice there is enough action or flow through the chamber 50 so that it does not become clogged.

The sand catching means 15 is provided to prevent sand accumulation above the separable connecting means 14 and around the pump to a degree that would interfere with the pumping action or freeze the barrel so it could not be removed. Said means may comprise a tube 60 of substantial length and arranged within a tubing section 40. The tube 60 is preferably of such a diameter as to provide an annular space 61 between it and the tubing section 40 so that easy insertion into and removal from the casing may be effected. A preferred manner of supporting the tube 60 is to mount the same, as by means of an end plate 62 on the lower end thereof, between the adapter 44 and the nut 48. In this manner the tube 60 is fixedly held and can be removed with the pump and, in effect, becomes part of the pump assembly. The tube 60 provides an elongated chamber 63 in which the barrel 10, the plunger 11, and the lower portion of the sucker rods 12 are located and it

evident that said chamber 63 receives the fluid discharge from the top cage 16. It will be further seen that any sand which may settle out of the fluid thus pumped, will be caught and collected by or within the tube 60 and will accumulate in the lower portion 63a of the chamber 63, the bottom of which is closed by the wall 62.

In order to prevent sand that settles out of the fluid from entering the annular space 61 and thus reaching the separable anchor means 14, the upper end of the tube 40 may be provided with sealing means 64 to close the upper end of said space 61. The sealing means 64 may comprise an upper extension tube 65 for the tube 60, a plurality of reverse bevel sealing cups 66 carried by the extension tube, and cup hold-down rings 67 alternately spaced with the cups 66. The cups 66 are designed to bear against the inner wall of the tubing section 40 and thus to seal off the space 61 from the discharge of the pump.

The tubing section 40 will ordinarily have an unfinished inner surface and is of considerable length from the top of the well to the sealing point above-described and said surface will sometimes cause the sealing surfaces of the cups 66 to become unduly worn or possibly injured as the pump is being inserted into the casing. To insure a good seal and to compensate for wear of the cups 66, a casing or sealing nipple 40a is inserted into the tubing string and is connected, as by couplings 40b, between adjacent tubing sections to occur at the point where the sealing means occur. Said nipple 40a is provided with a smooth inner surface of somewhat smaller diameter than the inner diameter of the tubing string, generally. By this structure, the cups 66 can be somewhat smaller initially to have minimum frictional contact with the tubing as the pump is being inserted. When said cups encounter the nipple 40a, they will be relatively smooth and engage the smaller smooth inner surface of said nipple 40a with suitable sealing contact.

According to this structure the sand settling out of the fluid being pumped may flow into but cannot lodge around the catcher 15. As the sand accumulates in the sand catcher, the stroke of the barrel 10 may be shortened according to the degree of interference the sand offers to movement of the barrel. When the stroke becomes too short for practical pumping, the entire pump assembly may be withdrawn from the well as hereinbefore described. Since sand has been kept from fouling or clogging the separable anchor means 14, such withdrawal of the pump is rendered easy. After removal of the sand, the pump assembly may again be inserted into the well casing and the pumping operation continued.

Figs. 4, 5, 6 and 7 illustrate a traveling plunger type of pump with a top lock and incorporating another form of sand catching means. The pump may generally comprise a traveling plunger 70, a string of sucker rods 71 operable from the top of the well for reciprocating the plunger, a stationary barrel 72 associated with the plunger, a housing or casing 73 for the pump, a top lock assembly 74 for supporting the pump from said casing 73, and elongated means 75 which includes a sand catcher 76, affording means for connecting the lower portion of the pump to the top lock assembly, the structure being such as to provide for an abnormally long pump stroke.

The plunger 70 may comprise a top cage 80, carrying at its lower end a plunger tube 81 through the medium of a top plunger bushing 82. The lower end of the plunger tube carries a

plunger valve cage 83 having a ball 84 and a seat 85. The plunger assembly is completed by a bottom plunger nut 86.

The barrel 72 may comprise an inserted type 5 top collar 87, a jacket 88 connected to the collar 87, and a double valve cage 89 carried on the lower end of the jacket. Balls 90 and 91 may be carried by said cage. A bottom collar 92 may comprise the lower end of the barrel assembly. A 10 plurality of liners 93 are placed within the jacket 88 and between the top collar 87 and the cage 89. In the present instance it is preferred to 15 provide a barrel that is unusually long. For this purpose the jacket 88 is made sufficiently long so that it may house a number of liners as, for instance, seven liners.

From the above described plunger and barrel structure it may be seen that the plunger 70 may have a relatively long stroke in the barrel 72 and that upon an upstroke of said plunger, fluid will 20 be drawn into the chamber 94 of the cage 89 and, consequently, into the lower end of the chamber 95 formed by the liners 93. Upon a down stroke of the plunger, said fluid will pass 25 through the cage 83, into the hollow 96 of the plunger tube 81, out through ports 97 in the cage 80, and into the chamber 95 above the plunger 70.

The pump is disposed within the casing or 30 string of tubing 73 which may comprise an upper tube 100, a lower tube 101 connected by the top lock assembly 74, said assembly including an upper shoe 102 connected with the upper tube 100 and a lower shoe 103 on the lower tube 101 and connected with the upper tube. The shoes 102 and 103 clamp a lock seat ring 104 between them, said ring serving to support a top lock 35 mandrel 105 which may be inserted downwardly to seat on the ring 104. Said mandrel is held 40 from normal upward movement by a spring lock sleeve 106 mounted on the mandrel below the lock seat ring 104. The mandrel 105 carries a rod guide 107 having ports 108 and the mandrel has a central axial opening 109 for the free 45 passage of fluid from the chamber 95 into the casing tube 100 above the top lock assembly 74.

Inasmuch as it is desired to provide a large 50 sand catcher 76, the plunger and barrel structures are spaced from the top lock assembly to a degree desired for obtaining a sand catcher of large size. For this purpose, the means 75 for connecting the barrel structure to the top lock assembly may comprise a plurality of elongated 55 tubes 110 connected by couplings 111 to provide the desired length of sand catcher, the sand catching chamber 112 being established within the tubes 110. The lowermost of the tubes 110 connects with the top collar 87 and the uppermost one connects through a sleeve bushing adapter 113 and a sleeve bushing 114, with the mandrel 105. In keeping with the above structure, the string of sucker rods 71 includes one or more sucker rods 115, and a sucker rod 116 in addition to other upper sucker rods 117 extending upwardly in the well casing. Sucker rod couplings 118 and 119 may connect the sucker rods 115, 116 and 117 to form the string 71.

The sucker rod 115 may be of conventional design except that its coupling portions 120 are machined off to permit passing the rod through the guide 107. The lower coupling portion of the rod 116 and the couplings 118 are machined smaller for the same purpose. The upper coupling portion 121 of the sucker rod 116 is also

machined down to permit the rod guide 107 to be passed over said upper end when the pump is being assembled at the well surface. In addition, the lower coupling portion of the rod 116 may be machined to provide opposed flats 122 forming abutment flanges 123 adapted to engage a seat 124 in the rod guide when the pump is desired to be withdrawn from the well.

Since the pump is carried at a remote point from the top lock assembly 74, said assembly can be positioned at a point above where fluid borne sand can reach it to clog the same. The remote arrangement of the pump and said top lock assembly further provides for an elongated sand catcher 75 which comprises the upper portion of the chamber 95, the interior of the tubes 110 and couplings 111, and the axial passage 109 of the rod guide 107. As sand accumulates in the sand catcher, the pump stroke may be accordingly shortened as in the earlier form of the invention. However, since the sand catcher is of extra large capacity because of the additional length provided by the structure, the pump may function for a relatively long time period before its stroke becomes too short for practical pumping. By lifting on the sucker rod string 71 until the flanges 123 engage the seat 124 and by exerting a sufficient upward pull on said string, the spring fingers of the lock sleeve 106 may be forced inwardly so that the entire pump structure can be pulled through the ring 104 and then out of the well.

Having described only typical preferred forms and applications of my invention, I do not wish to be limited or restricted to the specific details herein set forth, but wish to reserve to myself any variations or modifications that may appear to those skilled in the art and fall within the scope of the following claims.

Having described my invention, I claim:

1. Well pumping apparatus including, a casing, a plunger, means separably anchoring the plunger in the casing, a movable pump barrel operatively associated with the plunger, said plunger and barrel being disposed within the casing to leave an annular space therebetween, and a sand catcher carried by the plunger and arranged in said annular space whereby sand settling out of pumped fluid above the catcher is accumulated by the catcher and kept from the anchoring means, said catcher including a tubular member extending above the top of the pump plunger.

2. Well pumping apparatus including, a casing, a plunger, means separably anchoring the plunger in the casing, a movable pump barrel operatively associated with the plunger, said plunger and barrel being disposed within the casing to leave an annular space therebetween, and a sand catcher carried by the plunger and arranged in said annular space whereby sand settling out of pumped fluid above the catcher is caught by the sand catcher and kept from the anchoring means, said sand catcher including a tubular member extending above the top of the pump plunger, and sealing means carried by the upper outer portion of said tubular member and having sealing engagement with the inner surface of the casing.

3. Well pumping apparatus including, a casing, a plunger, means separably anchoring the plunger in the casing, a movable pump barrel operatively associated with the plunger, said plunger and barrel being disposed within the casing to leave an annular space therebetween, and

5 a sand catcher carried by the plunger and arranged in said annular space to catch sand settling out of fluid in the casing above the catcher and to keep such sand from the anchoring means, said sand catcher including a tubular member extending above the top of the pump plunger, and sealing means carried by the upper outer portion of said tubular member and having sealing engagement with the inner surface of the casing, the sealing means including a plurality of sealing cups and alternately arranged hold-down rings.

10 4. A well pumping apparatus including a fixed casing, a stationary pump plunger, a reciprocating barrel cooperating with the plunger, a bottom lock separably connecting the casing and the plunger, a sand catcher supported from the bottom lock and extending upwardly to a point above said plunger, and means for sealing between the top of the sand catcher and said casing the upper end of the sand catcher being open to receive sand settling from fluid above the catcher.

15 5. A well pump operable in a well casing and including, two cooperating elements, one a plunger the other a barrel, one element having its lower end releasably fixed in the casing, and a sand catcher carried by the releasably fixed element and extending upwardly in the casing from the lower end portion of the fixed element to a point above both of said elements, the upper end of the catcher being sealed with the casing and being open to receive sand settling out of fluid in the casing above the catcher.

20 6. A well pump operable in a well casing and including, a plunger, a releasable anchor mounting the plunger in the casing, a pump barrel engaged to reciprocate over the plunger, and a sand catcher supported at the lower end portion of the plunger and extending upwardly in the casing to a point above the plunger and barrel, the upper end portion of the catcher engaging the casing checking flow of sand from fluid above the catcher down around the catcher to the anchor, the upper end of the catcher being open to receive such sand.

25 7. A well pump operable in a well casing and including, a plunger, a releasable anchor mounting the plunger in the casing, a pump barrel engaged to reciprocate over the plunger, a sand catcher including a tubular part having its lower end coupled to the plunger and extending upwardly to a point above the plunger and barrel, and means sealing between the upper end portion of said part and the casing excluding fluid from between the said tubular part and the casing, the upper end of the catcher being open to receive sand settling out of fluid in the casing above the catcher.

30 8. A well pump operable in a well casing and including, a plunger, a releasable anchor mounting the plunger in the casing, a pump barrel engaged to reciprocate over the plunger, a sand catcher including a tubular part having its lower end coupled to the plunger at the lower end thereof and extending upwardly to a point above the plunger and barrel, and a fluid seal between the upper end portion of said part and the casing, the upper end of the catcher being open to receive sand settling out of fluid in the casing above the catcher.

35 9. A well pump operable in a well casing and including, two cooperating elements, one a plunger the other a barrel having sliding engagement over the plunger, one element being re-

leasably fixed in the casing, and a sand catcher carried by the releasably fixed element and extending upwardly in the casing around both of said elements to a point above both of said elements, the upper end of the catcher being sealed with the casing and being open to receive sand settling out of fluid in the casing above the catcher.

10. A well pump operable in a well casing and including, a plunger, a releasable anchor mounting the plunger in the casing, a pump barrel engaged to reciprocate over the plunger, a sand catcher including a tubular part having its lower end coupled to the plunger and extending upwardly around the barrel with clearance and to a point above the plunger and barrel, and means sealing between the upper end portion of said part and the casing excluding fluid from between the said tubular part and the casing, the upper end of the catcher being open to receive sand settling out of fluid in the casing above the catcher.

11. A well pump operable in a well casing and including, a plunger, a releasable anchor mounting the plunger in the casing, a pump barrel engaged to reciprocate over the plunger, a sand catcher including a tubular part having its lower end coupled to the plunger and extending upwardly to a point above the plunger and barrel, and means sealing between the upper end portion of said part and the casing excluding fluid from between the said tubular part and the casing including a plurality of alternately arranged sealing cups and hold-down rings, the upper end of the catcher being open to receive

20

35

sand settling out of fluid in the casing above the catcher.

12. A well pump operable in a well casing and including, a plunger, an anchor at the lower end end of the plunger releasably mounting the plunger in the casing, a pump barrel engaged to reciprocate over the plunger from the upper end of the plunger, a tube having its lower end secured at the point of connection between the plunger and anchor and extending upwardly around the plunger with clearance and extending to a point above both the plunger and barrel, and sealing means carried by the upper end portion of the tube sealing with the interior of the casing, the upper end of the tube being open to receive sand settling out of fluid in the casing above the tube.
